UNITED STATES PATENT OFFICE.

CHARLES APPLE, OF WASHINGTON, PENNSYLVANIA.

DESIGN FOR A PATTERN FOR WINDOW-GLASS.

SPECIFICATION forming part of Design No. 22,982, dated December 26, 1893.

Application filed November 17, 1893. Serial No. 491,274. Term of patent 7 years.

To all whom it may concern:

Be it known that I, CHARLES APPLE, a citizen of the United States, residing at Washington, in the county of Washington and State 5 of Pennsylvania, have invented certain new and useful Improvements in a Design for Window-Glass, &c.; and I do hereby declare the following to be a full, clear, and exact description of the invention, which will enable others 10 skilled in the art to which it appertains to make and use the same.

My new design is to be used on heavy plate or window glass, or "cathedral glass" as it is known to the trade. That variety of plate 15 glass is designed particularly for use in churches and elsewhere, where a soft and mellow light is to be obtained. Plate glass ornamented after my design is well adapted for these uses, since a large proportion of any 20 direct sun rays passing through the same are intercepted and the effects of lights and shadows thereby produced are very beautiful.

In the accompanying drawings: Figure 1 is 25 a plan view of a piece of cathedral glass ornamented with my design; Fig. 2, a side view of the same, and Fig. 3, a plan view very much enlarged.

In all of the above views corresponding 30 parts are designated by the same letters of reference.

The principal feature of my new design consists in a raised figure A, having three irregular facets arranged on the entire surface of the glass.

In the drawings these figures are arranged 35 irregularly, without any attempt to conform to any particular design or conformation. Each raised figure A, has three facets, as shown particularly in Fig. 3. The facet *a*, is triangular in shape and extends out from the surface of the glass at a slight angle, and converges to the apex *b*. The facets *c*, and *d*, are 40 also triangular but are of smaller size than the facet *a*, and extend out from the surface of the glass at a greater angle than the facet *a*, converging also to the apex *b*. The facets *c* and *d*, are of the same size and have the same 45 angle.

What I claim is—

The design for a pattern for window glass, 50 &c., herein shown and described.

In testimony whereof I affix my signature in presence of two witnesses.

CHARLES APPLE.
